UNITED STATES PATENT OFFICE.

FRANK E. YOUNG AND CHARLIE A. BRAGG, OF LOOMIS, NEBRASKA.

SPARK-ARRESTER.

1,086,973.

Specification of Letters Patent.

Patented Feb. 10, 1914.

Application filed June 28, 1912. Serial No. 706,433.

To all whom it may concern:

Be it known that we, FRANK E. YOUNG and CHARLIE A. BRAGG, citizens of the United States, residing at Loomis, in the 5 county of Phelps, State of Nebraska, have invented certain new and useful Improvements in Spark-Arresters; and we do hereby declare the following to be a full, clear, and exact description of the invention, such as 10 will enable others skilled in the art to which it appertains to make and use the same.

This invention relates to spark arresters and has for its object to provide a spark arrester which may be secured upon a smoke 15 stack of a locomotive or other engine to prevent the escape of sparks from the upper end of the stack.

Another object is to provide a spark arrester having a vane projecting therefrom so 20 that the arrester will be properly turned by the air currents to position the screened portion thereof to the proper side of the stack during movement of the engine so that the sparks will strike thereagainst and thus 25 be prevented from escaping and probably causing fire or other damage.

Another object is to construct the spark arrester in such a manner that it will be readily positioned upon the end of the stack 30 and freely rotate thereon.

A further object is to provide a spark arrester of this type in combination with a trap and discharge pipe to be secured around the stack adjacent the end thereof to receive 35 the sparks, cinders and so forth from the spark arrester and properly discharge the same.

A still further object is to generally improve the construction and increase the efficiency of devices of this character and produce a spark arrester and trap which may be readily positioned upon the smoke stacks now in general use at the minimum cost.

With the above and other objects in view, 45 our invention will be more fully described illustrated in the accompanying drawings, which show a preferred embodiment of our device and then specifically pointed out in the claim which is attached to and forms 50 a part of this specification.

In the drawings:—Figure 1 is an elevational view of the complete device applied to a smoke stack of conventional form. Fig. 2 is a vertical longitudinal section on the line 55 2—2 of Fig. 1. Fig. 3 is a horizontal section on the line 3—3 of Fig. 2. Fig. 4 is a

detail perspective view of the lower portion of the spark arrester. Fig. 5 is a detail view of the removable ring for the upper edge of the smoke stack. Fig. 6 is a detail view of the removable trap for engagement around the smoke stack.

Referring more specifically to the drawings, in which similar reference numerals designate corresponding parts throughout, 65 10 designates the smoke stack having the beaded upper end 11 around which the sectional ring 12 is engaged, the sections of said ring being hinged together as shown at 13. One of said sections carries the tongue 14 at 70 its free end for engagement between the upper and lower flanges 15 of the opposite section and the pin 16 is passed through the flanges 15 and the tongue 14 to securely lock the ring upon the flange 11. It will be understood that each section of the ring 12 carries inwardly directed flanges 15, previously mentioned, for engagement above and below the outwardly beaded upper end 11 of the smoke stack 10. It will also be understood that the end of the section within 75 which the tongue 14 is received between the flanges 15, is bifurcated, as shown at 15.

When the sections of the ring 12 are properly clamped around the beaded end 11 85 of the stack 10 the said ring forms a track upon which the spark arrester rotates, as will now be described.

The spark arrester comprises principally a lower band 17, an upper band 18 held in proper spaced relation by means of the uprights 19, and secured to the bands 17 and 18 and the uprights 19 is the screen 20 which is bent into substantially semi-circular form in cross section, the vertical edges 95 thereof being parallel and at substantially diametrically opposite points. The screen top member 21 is secured upon the upper ring 18 completely covering the latter. The vane 22 carries the reduced extension 23 100 which is bent around the ring 18 and secured thereto, with the extremity of said extension securely fastened to the vane 22, as shown at 24, thus securely fastening the vane to the upper end of the spark arrester. 105 The edge of the screen top member 21 is preferably securely held against the upper ring 18 and the extension ring 23. The screen 20 is also preferably secured to the inner faces of the rings 17 and 18 and the 110 uprights 19 as will be clearly seen upon the drawings.

Projecting inwardly from the inner face of the lower ring 17 is a series of stub shafts 25 carrying the upper rollers 26 for engagement upon the upper face of the ring 12 5 and a similar series of stub shafts 27 is positioned below the series 25, said lower stub shafts 27 carrying the rollers 28 for engagement against the under face of the ring 12, thus properly supporting the spark 10 arrester for free rotary movement around the smoke stack 10. Secured to the inner face of the band 17 are the brackets 29 having the upper and lower arms 30 and 31 respectively between which are mounted the 15 vertical spacing rollers 32 which are positioned between the rollers 26 and the rollers 28 and engage against the periphery of the ring 12 to properly retain the band 17 in spaced relation to the ring 12.

20 Positioned around the stack 10 a short distance from the upper beaded end 11 thereof is the trap 33, the vertical edge of which is slightly outwardly of the vertical edge of the band 17, as the diameter of the 25 trap 33 is greater than the diameter of the band 17. The trap 33 has a slanting bottom 34 which is provided with a suitable central opening to accommodate the smoke stack 10 and at the lowest portion of the bottom 34 30 of said trap, the upper end of a suitable discharge pipe 35 is secured. The trap 33 is preferably braced by means of the strap 36 having one end secured thereto at a point opposite the connection of the discharge 35 pipe 35 therewith, while the opposite end of said strap is secured to the engine body. It will also be evident that the discharge pipe may extend to any desired point and may be provided with a suitable valve 37 40 for normally closing the lower end thereof.

From the foregoing it will be evident that we have provided a spark arrester which will be of extremely simple form and construction and which will, by action of the 45 air currents upon the vane 22 be properly rotated upon the upper end of said smoke stack, the construction of the ring 12 and the rollers 26, 28 and 32, assuring proper and free rotation of the spark arrester, it will 50 also be apparent that as the spark arrester

is properly rotated, the sparks and cinders escaping from the upper end of the smoke stack 10 will be directed against the screen top member 21 and that the cinders will fall between the ring 12 and band 17 into 55 the trap 33 from which they will gradually enter the discharge pipe 35. The discharge pipe 35 may be emptied of its contents, whenever desired by simply opening the valve at the lower end thereof.

60 While we have shown and described the preferred form of our device, it will be understood that minor changes in the details of construction may be made within the scope of the claim without in the slightest 65 degree departing from the spirit of our invention.

What we claim is:—

In a rotatable spark arrester, the combination with a smoke-stack having a beaded 70 upper end of a track-ring having a continuous groove in its inner periphery, said ring being detachably secured to the end of the smoke-stack, the bead of the stack engaging in the groove and holding the ring in position, a body member including upper and lower bands, uprights connecting said bands, a foraminous cover for the upper band, a semi-cylindrical foraminous member secured to the bands and to the uprights, pairs 75 of rollers extending from the inner periphery of the lower band, the axes of the said rollers disposed in a horizontal plane, a plurality of rollers carried by the inner periphery of the band and having their axes 80 vertically disposed, the vertically disposed rollers engaging the outer periphery of the track-ring and the horizontally disposed rollers engaging the upper and lower faces 85 of said rings to rotatably support the body 90 member, and a trap disposed below said body member.

In testimony whereof, we affix our signatures, in presence of two witnesses.

FRANK E. YOUNG.
CHARLIE A. BRAGG.
